UNITED STATES PATENT OFFICE.

FRANK PICONE, OF TOMBSTONE, ARIZONA.

ORE-CONCENTRATOR.

1,076,740.

Specification of Letters Patent. Patented Oct. 28, 1913.

Application filed May 14, 1913. Serial No. 767,612.

To all whom it may concern:

Be it known that I, FRANK PICONE, citizen of the United States, residing at Tombstone, in the county of Cochise and State of Arizona, have invented certain new and useful Improvements in Ore-Concentrators, of which the following is a specification, reference being had to the accompanying drawings.

10 This invention relates to improvements in ore concentrators and more particularly to a pneumatic ore concentrator for the treatment of auriferous materials.

15 The invention has for one of its further objects, the provision of an improved construction of riffle concentrating table embodying means for separating the precious material into several sizes or grades.

20 The invention has for another object, the provision of a pervious supporting bed for the ore body, means to force air under pressure upwardly through the pervious bed to cause the ore body to pulsate, and additional means for transversely reciprocating the 25 table.

25 The invention has for still another object to provide a pneumatic ore concentrator which is very simple in its construction, may be manufactured at small cost and is highly reliable and efficient in practical operation.

30 With the above and other objects in view, as will become apparent as the description proceeds, the invention consists in certain constructions, combinations and arrangements of the parts that I shall hereinafter fully describe and claim.

35 For a full understanding of the invention, reference is to be had to the following description and accompanying drawings, in 40 which—

Figure 1 is a side elevation of an ore concentrator embodying the present invention. Fig. 2 is a top plan view thereof; Fig. 3 is an end elevation; Fig. 4 is a fragmentary 45 longitudinal section taken on the line 4—4 of Fig. 2; Fig. 5 is a transverse section taken on the line 5—5 of Fig. 2.

45 Referring in detail to the drawings, 5 designates the corner posts or uprights of a supporting frame, and 6 the longitudinal and transverse connecting bars thereof. One pair of the corner uprights of the frame are of greater height than the other and the longitudinally inclined frame bars 7 connect 55 said uprights at their upper ends. Upon these longitudinal bars 7, the concen-

trating table to be later described in detail is mounted.

A bellows 8 is mounted in the machine frame, the side walls of said bellows being attached at their upper edges to the frame 18 of the table. A transversely disposed shaft 9 is mounted in suitable bearings 10 provided upon the uprights 5 at one end of the machine. Upon this shaft, the spaced eccentrics 11 are secured, and eccentric collars or straps 12 are loosely engaged upon the fixed eccentrics 11. By adjusting these straps 12 and securing them in their adjusted positions by means of the set screws 13, the throw may be varied, as desired. The outer eccentrics 12 are connected to one end of the bottom board or wall of the bellows 8 by means of the rods 14.

15 designates the driven shaft which is mounted upon the frame uprights 5 above the shaft 9. One end of this shaft is provided with a belt wheel or other means whereby the shaft may be driven from an engine or other suitable source of power. 20 Upon said shaft, a gear wheel 16 is fixed, and this gear wheel meshes with the pinion 17 fixed upon the shaft 9.

25 My improved ore concentrating table embodies an outer boundary wall or frame 18 which is in the form of an elongated parallelogram and to the same, a lattice structure indicated at 19 consisting of cross diagonally extending strips are secured. Upon this open framework or lattice, the pervious flexible bottom 20 of the table is secured at its outer edges. This table bottom is made up of a lower layer of wire cloth 21. Upon this wire cloth one or two layers of burlap 22 are arranged, and a final upper sheet of 30 closely woven silk, broadcloth or other suitable material indicated at 23 is secured.

35 The concentrating table is arranged between and in parallel relation to the upper frame bars 7 and upon the upper surface of the pervious bottom of the table, the concentrating riffles 24 are arranged, said riffles being secured to the lattice work 19 of the table structure. These concentrating riffles are disposed in parallel relation transversely of the table and extend obliquely thereacross. It is to be understood that the open framework or lattice 19 is flush with the upper edges of the boundary walls 18 of the table so that the concentrating riffles 40 extend above the plane of said boundary walls. The skimmer-riffles 25 are disposed 45

at right angles to the concentrating riffles and between the same. These skimmer riffles consist of short cleats which are screwed or otherwise secured to the lattice work 19. At their upper ends, the skimmer riffles engage closely with the concentrating riffles 24 while the lower ends of the skimmer riffles are spaced from the contiguous concentrating riffles 24. These skimmer riffles in conjunction with the concentrating riffles form what is in effect a plurality of rectangular ore receiving pockets on the upper surface of the table. By spacing the lower ends of the riffles 25 from the riffles 24, a passage-way is provided from one pocket to the other transversely across the table.

Upon one of the upper longitudinal frame bars 7, a longitudinal shaft 26 is mounted. This shaft is provided adjacent to its opposite ends with the double eccentrics indicated at 27 which are similar in construction to the eccentrics 11 and 12 previously described. To the strap of the outermost eccentric, the rods or arms 28 are connected, the other ends of said rods being pivotally connected to one of the side walls of the table 18. One end of this shaft is provided with a beveled gear 29 which meshes with the teeth of a similar gear 30 secured upon the shaft 9.

From the above description, the construction and operation of the machine will be readily understood.

The ore is fed to the machine from a hopper 31, mounted between the upper ends of one pair of uprights 5, said hopper delivering the material upon a spreading and directing board 32 which is mounted upon the upper surface of the concentrating table at its upper end. The ore gravitates downwardly upon the flexible pervious bottom of the table and into the several receiving pockets formed by the riffles 24 and 25. The heavier particles of ore will constitute the bottom layer of the ore body while the barren material being lighter in specific gravity, will constitute the upper strata thereof. The skimming riffles 25 as clearly shown in Figs. 4 and 5 extend above the upper edges of the riffles 24. The particles of ore are caught by the riffles 24 and directed toward one side of the machine where they are discharged into suitable receptacles. The height of the riffles 24 gradually decreases from the upper to the lower ends of the table, and the riffles 25 correspondingly decrease in height. The larger particles are discharged from the table between the adjacent upper riffles 24 and as the material descends over the table, the finer grades are successively discharged therefrom. Thus the ore is graded at the same time that it is separated from the barren and worthless materials. These barren materials which as before stated, are lighter than the ore are held by the short riffles 25 which extend at right angles to the riffles 24

and directed thereby over the opposite edge of the concentrating table. During the movement of the ore, the bellows 8 is actuated by the eccentrics 11 and rods 14 to force air upwardly through the pervious bottom of the concentrating table, thus causing the ore bed to rise and fall so that the lighter particles will pass over the skimming riffles 25. Simultaneously with this pulsating movement of the ore body, the table is transversely reciprocated by means of the eccentrics 27 on the shaft 26, whereby the movement of the ore transversely of the table and its discharge therefrom is effected.

The longitudinal side bars of the outer boundary wall 18 of the table are provided with pockets or recesses 33 to receive the lugs or extensions 34 secured to the longitudinal bars 7 of the supporting frame whereby said table is supported in position. To the opposite sides of the table, and the side bars 7 of the frame structure, strips of canvas 35 are attached, said canvas being sufficiently loose to permit of the movement of the table. These canvas strips are provided for the purpose of preventing dust and dirt from entering between the table and its supporting frame and interfering with the proper operation of the machine.

From the above it will be seen that I have produced a simply constructed and very efficient machine for operating upon all materials of different specific gravities, to effect the separation of the valuable minerals from the baser materials and simultaneously grading the former.

A machine embodying the structural features above described may be constructed at comparatively small cost and is also very durable and reliable in operation.

While I have shown and described the preferred construction and arrangement of the several elements, it will be understood that the invention is susceptible of considerable modification without departing from the essential features or sacrificing any of the advantages thereof.

Having thus described the invention, what is claimed is:

1. In an ore concentrator, a table having a plurality of parallel transversely disposed riffles upon its upper surface and a second series of riffles arranged between and extending at right angles to said first named riffles, said latter riffles projecting above the upper edges of the transverse riffles and each having one end spaced from the contiguous transverse riffle, and means for reciprocating said table.

2. In an ore concentrator, a table provided upon its upper surface with a plurality of parallel transverse obliquely disposed riffles and a second series of spaced riffles arranged between the transverse riffles and extending at right angles thereto, said latter riffles pro-

jecting above the upper edges of the trans-
verse riffles and each having one end spaced
from the contiguous transverse riffle, and
means for transversely reciprocating said
table.

3. In an ore concentrating machine, a sup-
porting frame, a table mounted for trans-
verse movement in said frame, said table hav-
ing a pervious bottom, a plurality of trans-
versely disposed parallel riffles arranged
thereon, a second series of obliquely dis-
posed riffles arranged between the transverse
riffles and each having one end spaced from
the contiguous transverse riffle, said latter
15 riffles projecting above the upper edges of

the transverse riffles, and both sets of riffles
gradually decreasing in height from one end
to the other of the table, means for forcing
air upwardly through the pervious bottom
of the table to cause the ore body thereon to 20
pulsate, and means for simultaneously trans-
versely reciprocating the table.

In testimony whereof I hereunto affix my
signature in the presence of two witnesses.

FRANK PICONE.
